US00D967686S

(12) **United States Design Patent** (10) **Patent No.:** **US D967,686 S**
Demers et al. (45) **Date of Patent:** **** Oct. 25, 2022**

(54) **TOOL HANDLE**(71) Applicant: **LOWE'S COMPANIES, INC.**,
Mooresville, NC (US)(72) Inventors: **Brian Joseph Demers**, Huntersville,
NC (US); **Joseph Allen Berlepsch**,
Mooresville, NC (US)(73) Assignee: **LOWE'S COMPANIES, INC.**,
Mooresville, NC (US)(**) Term: **15 Years**(21) Appl. No.: **29/724,345**(22) Filed: **Feb. 14, 2020**CPC B25B 15/02; B25B 15/04; B25B 15/001;
B25B 15/008; B25B 25/002; B25G
1/005; B25G 1/046; B25G 1/085; B25G
1/063

(57) CLAIM

The ornamental design for a tool handle, as shown and described.

DESCRIPTION

FIG. 1 is a perspective view of a tool handle according to the present invention;

FIG. 2 is a plan view of the top side of the tool handle of FIG. 1;

FIG. 3 is a plan view of the bottom side of the tool handle of FIG. 1;

FIG. 4 is an elevational view of the front side of the tool handle of FIG. 1;

FIG. 5 is an elevational view of the rear side of the tool handle of FIG. 1;

FIG. 6 is an elevational view of the left side of the tool handle of FIG. 1; and,

FIG. 7 is an elevational view of the right side of the tool handle of FIG. 1.

The broken lines in the drawings illustrate portions of the tool handle and environmental structure of an impact wrench that form no part of the claimed design.
